Primary Examiner — Ian Simmons*Assistant Examiner* — Keith Frank(74) *Attorney, Agent, or Firm* — Epstein Drangel LLP;
Robert L. Epstein(57) **CLAIM**

The ornamental design for bottle, substantially as shown and described.

DESCRIPTION

FIG. 1 is a front, top and left perspective view of a bottle showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings showing the bottle illustrate portions of the bottle that form no part of the claimed design.

1 Claim, 5 Drawing Sheets(56)
